ATTORNEYS

UNITED STATES PATENT OFFICE.

DANIEL STEWART SELLERS, OF INDIANAPOLIS, INDIANA.

HANGER.

Application filed November 2, 1922. Serial No. 593,622.

My invention relates to improvements in hangers, more particularly that type of hanger which is used to secure pipes or the like to a ceiling.

5 An object of my invention is to provide a hanger of the type described which has pipe means removably associated therewith which may be moved after the hanger is secured in place, whereby the means may be 10 aligned with the pipe being supported thus assuring a straight length of pipe extending between a number of hangers.

15 A further object of my invention is to provide a device of the type described that is shaped so as to be supported when embedded in concrete floors or the like.

20 A further object of my invention is to provide a device of the type described which is simple in construction, durable and efficient for the purpose intended and which is not likely to easily get out of order.

25 Other objects and advantages will appear in the following specification, and the novel features of the invention will be particularly pointed out in the appended claims.

My invention is illustrated in the accompanying drawings forming part of this application, in which

30 Figure 1 is a side elevation of the device showing it operatively applied in place,

35 Figure 2 is a section along the line 2—2 of Figure 1,

Figure 3 is a top plan view of the device, and

35 Figure 4 is a section along the line 4—4 of Figure 1.

In carrying out my invention I provide a hanger indicated generally at 1 which is formed with a casing 2 and an upwardly extending supporting member 3. As clearly shown in Figure 2 the portion 3 has a recess 4 therein and is provided with a downwardly extending flange 5 at its upper end. The casing 2 has lugs 6 extending therefrom by means of which the device may be secured in place to the frame work 7 of the floor. The device is especially adapted for use in concrete floors and, as heretofore stated, is disposed in place upon the molding 7 by 50 nails 8 or the like. The concrete or cement may now be poured upon the flooring 7 and when hardened will securely hold the hanger 1 in place.

55 The construction of the casing 1 is fashioned so as to permit the pipe supporting member 9 to be slidably carried thereby,

whereby the member 9 can be aligned with the pipe even though the hanger 1 is slightly out of alignment. In this manner the hangers 1 may be disposed in substantial alignment in the ceiling 10 thereby obviating the necessity of accurately aligning the hangers. If the hangers are slightly out of alignment with each other the pipe supporting members 9 may be moved with respect to the hangers 60 so as to accurately align the members 9 with respect to the pipes 11. The members 9 are U-shaped and are adapted to receive a clamp 12 which in turn carries or supports the pipe 11. The clamp 12 is secured to the member 9 by means of a bolt 13.

In Figure 4 I have shown a top plan view of the member 9 and it will be noted from this figure that the lugs 14 of the member 9 are provided with curved sides 15 whereby 75 they may be first inserted into the casing 2 and then rotated through an arc of 90°, whereby the member is locked in place. The lugs 14 prevent further rotation of the member in the same direction. The shank 16 is 80 of the same width as the slot 17 in the bottom of the casing 2 and is also provided with rounded corners 18 whereby the shank may be rotated to an arc of 90° and be prevented from any further rotation in the same direction. It will also be noted from Figure 1 that the under side of the lugs 14 and the upper side of the lower floor of the casing 2 are serrated. The thickness of the lugs 14 permits the member 9 to be moved upwardly 85 so as to disengage the teeth 19 of the member 14 from the teeth 20 of the casing 2. The member 9 can therefore be moved with respect to the casing 2 and then be lowered, whereby it will be locked in place against 90 further movement.

From the foregoing description of the various parts of the device, the operation thereof may be readily understood. As heretofore stated the device is especially 100 constructed so as to be disposed in concrete or cement floors. The hangers 1 are disposed on the flooring 7 in any position desired, this position being determined by a prearranged plan. The concrete can now 105 be poured upon the flooring 7 and will entirely encase the hanger 1. It will be noted that the concrete will flow between the casing 2 and the flange 3, whereby the casing is firmly embedded in the floor, and provides a sufficient support to the hanger after 110 the concrete is hardened. The concrete also

flows into the recess 4 and aids in preventing lateral movement of the hanger 1 with respect to the floor. It is to be noted that the hangers 1 are arranged in substantial alignment with each other so as to be in substantial alignment with the pipe 11 that is to be carried by the hanger. The members 9 are now inserted into the casing so that the lugs 14 are aligned with the slot 17, whereby the lugs may be moved into the casing. The member 9 is now rotated through an arc of 90° and is prevented from further rotation by the construction of the lugs 14 and the shanks 16 as heretofore described. 15 The member 9 in each of the hangers 1 may be moved with respect to its hanger so that the members will be accurately aligned with each other and will readily support the pipe 11. The length of the casing 2 permits the 20 members 9 to be moved quite a distance with respect thereto. After the concrete or cement has set the frame work 7 may be removed and it will be noted that the hanger 1 is securely held in place. The hanger 1 25 is really a permanent fixture of the ceiling or floor 10. The bottom of the casing 2 is flush with the under side of the floor 10. In case it is desired to remove the pipe 11 the members 9 may be removed and it will 30 therefore be obvious that nothing projects below the undersurface of the casing 2, which, as heretofore stated, is flush with the under side of the floor 10.

The device is extremely simple in construction and provides an efficient and novel means for aligning the pipe supporting members with the hanger after the hanger has already been secured in place to the ceiling. 35

It should be noted that applicant's member 9 is provided with a depending fork portion through which the bolt 13 extends. 40

The bolt 13 is carried in two places, i. e., by both of the arms of the member 9. Both free ends of the plate or strip 12 are carried by the bolt 13. From this construction it will be noted that the member 9 is adapted to carry a pipe 11 which weighs approximately twice as much as the ordinary pipe that can be carried by the devices now on the market. In the ordinary devices on the market, the bolt 13 is carried by only one arm and only one end of the strap 12 is secured to the bolt. In many cases, the pipe 11 is heavy and causes the strap 12 to shear the bolt 13. With the present construction, however, this disadvantage is obviated, since the bolt 13 is carried in two places instead of one, and the strap 12 is carried or secured to the bolt 13 at both of its ends instead of at only one end. 45 50 55 60

I claim:

A device of the type described comprising a hanger, said hanger having a casing, said casing having a slot in its under surface extending substantially the entire length of the casing, the slot being of less width than the width of the casing for providing supporting ledges, these ledges being disposed on each side of the slot and having their upper surfaces serrated, a pipe carrying member having a shank, said shank having an enlarged head, the width of said head being sufficiently narrow to permit the head to enter the casing through the slot, and of sufficient length to rest upon the serrated portions of the ledges, said head having its diagonally opposite corners rounded to permit the shank to be turned 90° in one direction from the position assumed during its projection into the casing. 65 70 75 80
